UNITED STATES PATENT OFFICE.

FRANK F. KNOTHE, OF NEW YORK, N. Y.

DESIGN FOR A SUSPENDER-END.

SPECIFICATION forming part of Design No. 28,878, dated June 14, 1898.

Application filed October 12, 1897. Serial No. 654,998. Term of patent 7 years.

To all whom it may concern:

Be it known that I, FRANK F. KNOTHE, a citizen of the United States, residing at New York, in the county of New York and State 5 of New York, have invented and produced a new and original Design for Suspender-Ends, of which the following is a specification, reference being had to the accompanying drawings, forming a part thereof.

- 10 In said drawings, Figure 1 is a front elevation of a suspender-end embodying my design. Fig. 2 is a cross-sectional view showing the contour of one of the depending portions at a point intermediate its ends.
- 15 The leading or material feature of my present design consists in the depending portions A A, having a smooth surface, substantially flat in cross-section, with rounded edges and substantially straight from end to end, each 20 of the depending portions A having a central division-line terminating at the bottom in an opening to form a buttonhole, the effect being as though each depending portion were formed of a single strip starting at the top 25 and being bent at the center to form the buttonhole and being again brought back to the

upper end of the depending portion. Above the buttonhole a series of zigzag stitches E bridge the central line, and marginal stitches C C extend from the top of each of the depending portions to a point in proximity to the buttonhole, and from this point a continuation of this line of stitches forms a marginal line of stitches around the inner edge of the buttonhole. The upper ends of the two depending portions pass within a cast-off B at points somewhat separated from each other, so as to depend at different angles, giving a substantially V shape to the whole structure. The 30 stitches are of a color contrasting with the 35 color of the smooth surface of the material which they overlie, presenting a neat and effective appearance.

Having thus described my invention, what I claim as new is—

40 The design for a suspender-end as herein shown and described.

FRANK F. KNOTHE.
